UNITED STATES PATENT OFFICE.

JAMES MACKIRDY, OF NEW YORK, N. Y.

STAMP-VENDING MACHINE.

SPECIFICATION forming part of Letters Patent No. 660,913, dated October 30, 1900.

Application filed July 6, 1899; serial No. 722,954. (No model.)

To all whom it may concern:

Be it known that I, JAMES MACKIRDY, of the city of New York, borough of Brooklyn, in the county of Kings and State of New York, 5 have invented a new and Improved Stamp-Vending Machine, of which the following is a full, clear, and exact description.

My invention relates to an improvement in machines for automatically vending stamps 10 or other articles having a general similarity thereto, and comprises the novel features hereinafter described and claimed.

Reference is to be had to the accompanying drawings, forming a part of this specification, 15 in which similar characters of reference indicate corresponding parts in all the figures.

Figure 1 is a sectional side elevation of my device, certain portions being broken away to show interior mechanisms. Fig. 2 is a sectional front elevation of my device. Fig. 3 is a plan view thereof, the casing being in section; and Fig. 4 is a detail elevation showing the manner of connecting the operating-shaft with the actuating mechanisms for the 25 various reservoirs or receptacles.

The method employed in my device for delivering the stamps is to place the latter after being separated within a box or receptacle of a cross-section conveniently large to accommodate a stamp, the stamps being piled one upon the other, and to remove the stamps from said box or receptacle by means of a suction-cylinder provided with a piston inserted within the receptacle until it contacts 35 with the upper stamp of the pile. Then the piston is moved upward sufficiently to create a partial vacuum, which will attach the upper stamp to the bottom of the cylinder, whereupon the cylinder is raised and then 40 swung to one side, the stamp being freed by a slight downward movement of the piston. The various cylinders and pistons which are used in connection with stamps of various denominations are all operated from a common shaft. The actuating mechanism for 45 said pistons and cylinders is mounted loosely upon the shaft and is turned by means of a spring which is of sufficient power to overcome the resistance due to the friction of the 50 parts, but will slip by if the mechanism is locked; thus enabling one or more of the cylinders to be operated at once, according to

the number which are released by the insertion of the coin.

The device is mounted within a suitable 55 casing C. The stamps are placed in suitable reservoirs or receptacles G, which are of such cross-section as to receive a single stamp, the stamps being piled one upon each other until the reservoir is filled. I have herein shown 60 four of these reservoirs, each reservoir being designed, as shown by the index-plate C' of Fig. 1, to hold a stamp of a particular denomination. Mounted above each of these reservoirs is a cylinder B, which is supported 65 to slide within a ring F', said ring being supported within a yoke F³, which is formed upon one end of a bar F, said bar being mounted to slide in guides F². Each cylinder has a piston D within it, which has a limited 70 reciprocating movement within the cylinder, the extent of movement being limited by a pin d, which projects from the piston-rod D' through longitudinal slots b' in the upper portion of the cylinder. The piston is normally held in its raised position by means of a spring D², which surrounds the upper outer portion of the piston-rod and bears against the upper end of the cylinder. On the upper outer face of the cylinder is a notch b, which 75 is adapted to engage with a projection I on the casing in the manner and for the purpose hereinafter described.

To the upper end of the piston-rod D' is connected one end of a bell-crank lever E', 80 said lever being pivoted upon a cross bar or shaft E. The lower end of the bell-crank lever has a cam-roller e journaled therein, adapted to engage the outer surface of a cam P, loosely mounted to turn upon a cross-shaft 90 A. The bell-crank lever E' is acted upon by a spring e' so as normally to depress the cylinder D and to hold the cam-roller e in contact with the cam P. The cam P is provided with a notch formed by the inwardly-sloping 95 surface P' and the outwardly-sloping surface P², which will permit the cam-roller e to swing nearer to the center of the shaft A and will then raise it to its former position. The cam is also provided with a second drop or inwardly-sloping surface P³ and an outwardly-sloping surface P⁴, which brings the roller back to its ordinary position. As the cam 100 revolves the cam-roller e will drop into the

first large notch formed by the two sloping surfaces P' and P^2 , and as it strikes the second sloping surface P^2 the roller is moved outward and the cylinder is raised. As the 5 cam-roller drops into the notch the cylinder is depressed within the reservoir or receptacle G until it contacts with the stamps within said reservoir, the degree which the cylinder will drop depending upon the number of 10 stamps within the reservoir. The lower end of the cylinder is preferably provided with a ring b^2 , of rubber or similar flexible material, so as to maintain a close contact with the stamp. As the cam-roller e strikes the incline P^2 of the cam P the lever E' is operated first to lift the piston D', which causes a slight suction sufficient to cause the stamp to adhere to the lower end of the cylinder and be carried up therewith. The cylinder 15 is then raised until it is clear of the reservoir and is then swung to one side through the action of a cam Q, loosely mounted on the shaft A upon a cam-roller f, mounted in one end of the bar F, the normal position of 20 the cam-roller f being upon that portion of the cam Q having the shorter radius. After the cylinder has been raised by contact of the cam-roller e with the incline P^2 of the cam P the cylinder is then swung laterally clear of 25 the reservoir G by contact of the cam-roller f with the incline Q^2 of the cam Q. This swings the cylinder out over the hopper or inclined chute H and causes the tooth I' upon the bar I to enter the notch b in the upper 30 end of the cylinder, thus holding the cylinder, so as to prevent longitudinal movement thereof. While the cylinder is in this position the cam-roller e drops upon the incline P^3 of the cam P, thus causing the piston D 35 to be given a slight downward movement sufficient to free the stamp from the lower end of the cylinder, causing the stamp to drop in the hopper or chute H, secured to the inside of the casing C, from which it slides 40 through a slot in the lower end thereof into an outside trough H', said trough being covered by a lid H', which is hinged, so that it may be raised. The piston is then raised to 45 its normal position by contact of the cam-roller e with the incline P^4 of the cam P, and the cylinder B is brought back to its vertical position, as shown in Fig. 1, by the cam-roller f running down the incline Q' of the cam Q. The bar F, which controls the side 50 swinging of the cylinder, is acted upon by a spring f', which serves to hold the cylinder toward the cam and the roller f in contact therewith.

The mechanism just described, by which 55 the cylinder is operated, is duplicated for each of the reservoirs or stamp-receptacles, as is also the mechanism for controlling the operation of the cams, which is hereinafter to be described.

60 As previously stated, the two cams P and Q, by which the cylinder is operated, are loosely mounted upon the shaft A, but are

turned thereby through the intervention of the means now to be described.

Referring to Figs. 3 and 4, a disk or collar U is fixedly secured to the shaft A and has an arm U^2 pivoted upon its outer edge and normally extending in a radial direction. The pivot end of this arm lies within a slight recess U^3 , formed in one side of the disk or 70 collar U. This recess is of such nature that the lever when thrown to the radial position lies alongside of one side surface of the recess, the recess thereby limiting the position of the arm. In the other direction the notch 75 is sloping, so that the arm may be thrown backward at considerable angle, thus bringing the outer end thereof much nearer to the center of the shaft. The arm is held up in the radial position by means of a spring U' , 80 which is secured either to the shaft or to the collar U. Projecting from the side of the cam Q, which cam is secured to the cam P, is a pin Q^3 , so located as to be engaged by the outer end of the arm U^2 . The direction of rotation 85 of the shaft, as shown in Fig. 4, is to the left, the arm U^2 thus engaging the pin Q^3 , which causes the cams to turn. The spring U' is of sufficient strength to overcome the resistance to rotation of the cams caused by the friction 90 of the mechanism, but will give so as to allow the arm U^2 to swing backward and beneath the pin Q^3 if the cams are locked or otherwise held. Upon the opposite side of 95 the two cams or upon the surface of the cam P is secured a locking-disk R. This disk has a shoulder R^2 , which is adapted to engage the end of a locking-lever T', which is pivoted 100 upon a cross-shaft T. The end T^3 of this lever which engages the shoulder R^2 is turned 105 to one side, so that the body of the lever may clear a flange p, which projects from the side of the cam P adjacent to the shoulder R^2 . While the lever T' is in the position shown in 110 Fig. 1, the cams are locked, so that if the shaft A is turned the arms U^2 , carried thereby, will slip beneath the pins Q^3 and the cams will not be turned. The direction of turning 115 of the cams, as shown in Fig. 1, is to the right.

The locking-lever T' is held in locking position by means of the spring T^2 , and one end of said lever projects within the lower end of the coin-guiding chute K, which extends upwardly to the top of the casing, where the coins may be supported. The spring T^2 is a weak 120 spring, so that its influence may be overcome by the weight of a coin upon the lever T', so that the side projecting tooth T^3 may be raised clear of the shoulder R^2 , and its immediate upward swing is limited by the end p' of the flange p. This, however, is sufficient to free the cams, so that when the shaft A is turned the cams will also be turned, thus bringing the end T^3 of the lever T' in contact 125 with the incline R^3 , thus further raising this end of the lever and dropping the opposite end, which supports the coin. Until this has been done the coin is not free to escape from 130

the chute K; but after that end of the lever has been dropped by contact of the opposite end with the incline R³ the coin is freed and is dropped into the upper end of either the 5 chute K' or K², as the case may be, by which it is conducted to its proper receptacle.

The chute K, which controls the mechanism for delivering the one-cent stamps, has its 10 coins drop into the chute K' after being released from the lever T'. This chute K' conducts the coins to a change-making device L, which is shown in Fig. 1 and which will be hereinafter described. The arm T³ of the lever T' rides upon the outermost portion of the 15 disk R until the revolution has been nearly completed, whereupon it rides downward upon the incline R' to its normal or locking position. In order to insure the return of this lever to its locking position, the flange p is 20 used, one end of which is at sufficient distance from the center to insure engagement with the arm T³.

A stop-pawl O is provided, which prevents 25 backward rotation of the cams. This pawl is mounted upon a cross-shaft O² and has its end resting within a notch S' in a disk S, which is secured to the side of the cam R. The pawl O is held in position by means of a spring O'. The coins which are deposited through the 30 chutes K for all except for the one which controls the one-cent-stamp reservoir are deposited in the chutes K², which carry them downward, depositing them in a box or suitable receptacle K³.

35 The change-making device, which is shown in Fig. 1, is constructed as follows: The coins which are received through the chute K' drop into the conical upper end L² of a reservoir L, which is of such size as to nicely receive one-cent pieces, the same being the coins which are delivered through the chute K'. At the lower end of the reservoir L is a slide M, which has a hole therein adapted to register with the opening of the reservoir L and of the 40 same size. This slide M is of such thickness as to exactly accommodate five one-cent pieces. A spring m', which is attached to the inner end of this slide, serves to draw the same back to its normal position. Upon the 45 inner end of the slide M is mounted a side projecting pin m, which is adapted to engage the square inner end of the cam-flange M', which is mounted upon one side of a pivoted lever M³. This lever has its inner end projecting within the lower end of a coin-chute N, the upper end of said chute extending to a suitable opening in the side of the casing, as shown in Fig. 2. This lever is normally held in position to lock the slide M by means 50 of a spring M⁴. This spring is a weak spring, so that its influence is overcome by the weight of a coin upon the end of the lever. When a coin is inserted in the chute N, it drops upon the end of the lever M³ and depresses this end 55 of the lever and raises the opposite end until the end of the cam-flange is raised above the pin m, in which position the slide M is un-

locked, so that it may be drawn outward, thus 60 delivering five one-cent pieces. As the slide M is drawn outward the pin m strikes the incline m², so as to further raise this end of the lever, and thus free the coin from the chute, 65 allowing it to drop into the box K³. Upon the outer end of the cam-flange M' is mounted a thin flat spring M², which will yield to the 70 pin m as it passes outward and will then drop down, so that as the pin returns it will ride upon this spring and pass backward over the upper surface of the cam-flange M', thus insuring that the opposite end of the lever is 75 swung upward into position to receive the next coin.

In order that the party desiring change may 80 be able to see whether or not there is change in the receptacle, a glass plate L³ is inserted 85 in the front of the casing directly in front of the reservoir L, and the reservoir L is provided with openings L', located at convenient intervals therein, the same being preferably placed at a distance corresponding with the 90 thickness of five coins. The chute N is provided with an opening N' in the lower side of the same near its upper end, said opening being of such size that one-cent pieces if dropped therein will drop through and will 95 not affect the lever M³, while five-cent pieces will pass from the same to the lever M³.

By means of the mechanism described, by 100 which the cams are operated to actuate the delivering mechanisms, it is evident that any 105 number of delivering mechanisms may be operated from the same shaft, and yet only one, or as many as have been freed by the insertion of coins, is operated when the shaft is turned. The shaft A is provided with a crank A' upon one end by which it may be turned.

I have provided a device, which is shown in Fig. 1, which will indicate the fact when any one of the stamp-receptacles becomes empty. Mounted to slide in suitable guides 110 upon the face of the casing is a series of plates J², one plate being provided for each stamp-receptacle and located directly in front thereof. This plate is immediately above an opening in the casing which is covered with glass, 115 and has upon its outer face a suitable inscription which indicates that its particular reservoir is empty, and is normally held in raised position, so as to be invisible, by means of a pivoted lever J'. The upper end of the piston-rod D' has an arm J projecting to one side and moving in line with the inner end of the bar or catch J' when the cylinder is inserted within the stamp-receptacle. If the 120 stamp-receptacle contains any number of stamps, the cylinder will not descend a sufficient distance to cause the arm J to engage the catch J' and the slide J² will not be released. When, however, the stamps have been removed from this receptacle until it is practically empty, the arm J will finally contact 125 with the catch J' and release the slide J², which will drop down, so that its inscription will be visible, whereupon the intended pur-

chaser will be notified that stamps of that particular denomination are not to be had.

Although I have described my device as being used for selling stamps, it is evident that it may be used for delivering other articles which are capable of being raised by the suction device described, and I do not therefore wish to be limited to its use only for delivering stamps. It is also evident that the actuating mechanisms, consisting of the cams and the method of driving the same, may be used in connection with any form of delivering mechanism.

Having thus fully described my invention, I claim as new and desire to secure by Letters Patent—

1. A delivery device for vending-machines, comprising a suction-cylinder, a piston adapted to have a limited movement therein, a guide-ring surrounding the cylinder and having a sliding fit thereon, a bar secured to the ring and extending laterally from the cylinder, guides for said bar, a lever connected with the piston to reciprocate it, and actuating means for said lever and bar whereby the cylinder is reciprocated and then swung to one side, substantially as described.

2. A delivery device for vending-machines, comprising a suction-cylinder, a piston adapted to have a limited movement therein, a guide-ring surrounding the cylinder and sliding thereon, a bar secured to the ring and extending laterally from the cylinder, guides for said bar, a lever connected with the piston to reciprocate it, cam-rollers upon the lever and bar, and cams engaging said rollers whereby the piston and cylinder are reciprocated and are then swung to one side and the article deposited, substantially as described.

3. A delivery device for vending-machines, comprising a suction-cylinder and piston, and means for reciprocating them together, the piston having a limited movement in the cylinder, means connected with the piston for reciprocating both piston and cylinder, means for swinging the cylinder sidewise, and a catch engaging the cylinder to secure it against endwise movement after being swung sidewise, substantially as described.

4. A delivery device for vending-machines, comprising a cylinder, a piston having a limited movement therein, a guide supporting the cylinder to permit reciprocations thereof, means connected with said guide to move it laterally of the length of the cylinder, a lever pivoted to the piston, a fixed stop adapted to engage and hold the cylinder when it is swung to one side, and means for depressing the piston when the cylinder is in the side position, substantially as described.

5. A delivery device for vending-machines comprising a suction-cylinder, means for moving it into contact with the article to be delivered, means for lifting and transferring it sidewise, and a fixed catch engaging the cylinder to hold it against endwise movement

after being moved sidewise, substantially as described.

6. A delivery device for vending-machines comprising a suction-cylinder, means for moving it in contact with the article to be delivered, a guide-ring surrounding the cylinder and in which the cylinder has sliding movement, a bar connected with the ring and extending laterally from the cylinder, the said bar having guided movement, means for lifting said cylinder, and means for actuating said bar to swing the cylinder to one side, substantially as described.

7. A delivery device for vending-machines, comprising a cylinder having a stop-receiving hole in one side, the piston having a limited movement in the cylinder, a guide supporting the cylinder to permit reciprocations thereof, a bar connected with said cylinder-guide and extending to one side thereof, guides for said bar, permitting its longitudinal movement whereby the cylinder is moved laterally of its length, a lever pivoted to the piston, a fixed stop adapted to enter the hole in the cylinder when swung to one side, cam-rollers on the bar and lever, cams engaging the rollers, and means for turning them whereby the cylinder is lowered into contact with the article to be sold and is then raised and swung to one side, and the piston depressed within the cylinder to release the article, substantially as described.

8. In a vending-machine, a reservoir or receptacle for the article being sold, a suction device adapted to enter said receptacle and remove one of the articles therein, an indicator, a catch normally holding the indicator out of sight, and an arm projecting from the suction device and adapted to engage the catch to free the indicator when the receptacle becomes empty, substantially as described.

9. A delivery device for vending-machines, comprising a suction-cylinder, a piston having a limited movement therein, a spring bearing against the upper end of the cylinder, a lever connected with the piston to reciprocate it and the cylinder, means for actuating said lever, means for swinging the cylinder to one side, and a catch engaging the cylinder to hold it against endwise movement after being moved sidewise, substantially as described.

10. A delivery device for vending-machines, comprising a suction-cylinder, a guide-ring surrounding the same, a bar connected with said guide-ring and extending laterally from the cylinder, a piston having a limited movement in the cylinder, a lever connected with the piston to reciprocate both it and the cylinder, a cam for actuating said lever, and a second cam for actuating the said bar to swing the cylinder to one side, substantially as described.

11. A delivery device for vending-machines, comprising a cylinder, a piston having a limited movement therein, a spring connected

with the piston-rod and bearing against the upper end of the cylinder, a bell-crank lever connected with said piston to reciprocate the same and the cylinder, a spring acting on said bell-crank lever for normally depressing said cylinder, means for actuating said lever, and means for swinging the cylinder sidewise, substantially as described.

12. A delivery device for vending-machines comprising a cylinder, a piston having a limited movement in the cylinder, a spring bearing against the upper end of the cylinder, a spring-controlled guide supporting said cylinder to permit reciprocation thereof, a lever pivoted to the piston, actuating means for said lever whereby the piston is first lifted and then the cylinder is raised, actuating means for said guide, whereby the cylinder when raised is swung to one side, a stop adapt-

ed to engage and hold the cylinder when it is 20 swung to one side, and means whereby the piston is moved downward in the cylinder when the latter is in the side position and then restored to normal position, substantially as described.

13. In a vending-machine, a delivery device comprising a suction-cylinder adapted to be moved into contact with the article to be delivered and to be lifted and transferred sidewise, actuating means for imparting said 30 movements to said cylinder, and a locking device to hold said actuating means out of action, substantially as described.
